SPINNING TOP

Joseph W. Krapp, Katonah, N. Y.

Application June 5, 1948, Serial No. 146,779

Term of patent 7 years

(Cl. D34--15)

To all whom it may concern:

Be it known that I, Joseph W. Krapp, a citizen of the United States and a resident of Katonah, in the county of Westchester and State of New York, have invented a new, original, and ornamental Design for a Spinning Top, of which the following is a specification, reference being had to the accompanying drawings, forming a part thereof wherein:

Figure 1 is a perspective view of a spinning top, showing my new design;

Figure 2 is a top plan view showing the top;

Figure 3 is a bottom plan view showing the top; and

Figure 4 is a side elevational view showing the top.

I claim:

The ornamental design for a spinning top, substantially as shown.

JOSEPH W. KRAPP.
